EDGE BINDING

Mary Burnley Gwathmey, New York, N. Y.

Application January 20, 1934, Serial No. 707,446

5-Claims. (Cl. 2-274)

This invention relates to edge bindings such as are utilized for finishing, protecting and ornamenting the edges of blankets, garments, fabrics, and the like and provides a binding which is so constructed and arranged as to avoid the splitting, cutting or fraying of that portion thereof which embraces or protects the edge of the article to which it is applied.

The invention broadly comprehends an edge binding of the character set forth, comprising an elongated strip of woven, netted or knitted material which is so formed as to provide longitudinally extending oppositely disposed band portions for arrangement over and securement to opposite sides respectively of the fabric or article adjacent the edges thereof and outwardly extending flexible attenuations of said band portions for protecting the edge of the fabric or article.

The invention further provides an edge binding comprising an elongated strip of woven, netted or knitted material which is so constructed as to provide a pair of longitudinally extending closely woven band portions for covering and protecting the opposite sides of the fabric or article adjacent its edge and a loosely woven, strand, lace like or similarly flexible band portion providing a connection between said closely woven band portions for covering and protecting the edge of the fabric or article.

More specifically the invention contemplates an edge binding comprising an elongated strip of material which is so woven as to provide a pair of longitudinally extending oppositely disposed band portions of interwoven longitudinal and transverse threads for securement on opposite sides respectively of the fabric or article adjacent its edge and a longitudinally extending intermediate bight portion of flexible transversely disposed threads formed continuously with the transverse threads of said oppositely disposed band portions and providing a flexible fringe-like connection between said oppositely disposed band portions for covering and protecting the edge of the fabric or article.

The invention is further directed to an edge bound article which includes a binding strip disposed over the edge portion of the article and so constructed as to provide a loosely woven, strand, lace like or similarly flexible bight portion overlying or embracing the edge thereof, the construction of which renders it resistant to splitting, cutting or fraying and provides a different degree of flexibility from the body of the strip.

The invention is also directed to an edge bound article including longitudinal bands of material

disposed in parallel planes lying on opposite faces of the article and secured to the article adjacent its edge and a fringe-like finish or edging extending outwardly from the oppositely disposed bands for protecting the edge of the article.

With these and other objects in view, the invention provides a binding which may be produced in continuous lengths and at relatively small cost and which being resistant to splitting, cutting or fraying in the portion which protects the edge of the fabric or article, is efficient for its intended purpose.

With the above recited objects in view reference is made to the following specification and accompanying drawing in which there is set forth a preferred form of the invention.

In the drawing:

Fig. 1 is a side view of an edge portion of an article or fabric with an edge binding constructed in accordance with the invention applied thereto.

Fig. 2 is a sectional view taken approximately on line 2-2 of Fig. 1, on an enlarged scale.

Fig. 3 is a fragmentary magnified plan view of the edge binding.

Referring to the drawing by characters of reference, 10 indicates a continuous strip of woven, netted, knitted or other fabricated material of any desired length which may be produced in any preferred manner so as to provide a pair of longitudinally extending oppositely disposed closely woven band portions 11 and 12 and a longitudinally extending loosely woven strand, lace like or similarly flexible intermediate or medial bight portion 13 connected to the inner edges of the oppositely disposed band portions 11 and 12, which bight portion possesses greater flexibility than the band portions and hence is more resistant to splitting, cutting or fraying.

In the illustrated embodiment, the band portions 11 and 12 are produced by closely interwoven longitudinal and transverse threads 15 and 16, while the intermediate or medial bight portion 13 consists of loose or flexible transverse threads 17 which may be formed continuously with the transverse threads 16, the juncture of the band portions 11 and 12, with the intermediate or medial bight portion 13 being defined by longitudinal lock threads 18 which are so interwoven with the transverse threads 16 as to prevent ravelling or displacement of the innermost longitudinal threads 15 of the band portions.

The strip 10 is folded longitudinally over the edge of a blanket, garment, fabric, and the like, to serve as an edge binding therefor for finishing, protecting and ornamenting the same. As

illustrated in Fig. 2, the band portions 11 and 12 are disposed on opposite sides of the article 19 which may be a blanket, garment, fabric and the like, adjacent the edge thereof and are secured thereto by any desired means. The securing means may be an adhesive or one or more lines of stitching 20 as illustrated, two lines of stitching being employed, if desired, adjacent the free edges of the oppositely disposed band portions, while one line of stitching may connect the same with the fabric or article adjacent the intermediate or medial bight portion 13 which bight portion embraces or covers the edge of the fabric or article. It is to be understood, however, that the number and location of the lines of stitching is a matter of preference.

The intermediate or medial bight portion 13 being loosely woven or of readily flexible fringe-like strands, connected at their ends to the oppositely disposed band portions, functions to resist splitting, cutting or fraying incident to wear since the inherent flexibility thereof permits relative movement of the transverse strands, while providing an attractive covering for the edge of the fabric or article. Furthermore, the edge of the fabric or article being spaced from the inner surface of the bight portion, as illustrated in Fig. 2, it does not bind against or frictionally engage with the inner surface of the strands of the bight portion.

What is claimed is:

1. In combination, a fabric and a binding for protecting the edge thereof, said binding including an elongated strip of material having a pair of longitudinally extending oppositely disposed band portions, disposed on opposite sides of the fabric adjacent its edge, and a longitudinally extending intermediate bight portion of transverse threads only providing a fringe-like connection between the oppositely disposed band portions for covering and protecting the edge of the fabric, and means adjacent the edges of the oppositely disposed band portions for securing the same to the fabric and the intermediate bight

portion in spaced relation with the edge of the fabric.

2. In combination, a fabric and an edge binding therefor, consisting of longitudinal bands of material disposed in parallel planes lying on opposite faces of the fabric and secured thereto adjacent its edge and a fringe like edging of unwoven transverse threads located between said bands and overlying the edge of the fabric in spaced relation therewith.

3. A fabric and a binding for protecting the edge thereof, said binding including a pair of longitudinally extending band portions of interwoven longitudinal and transverse threads for securing on opposite sides respectively of the fabric adjacent the edge thereof, and contiguously arranged unwoven transverse threads located between the outer edges of said band portions and providing a flexible connection therebetween, means along the inner edges of the oppositely disposed band portions for preventing ravelling or fraying thereof, and means adjacent the first named means for securing the oppositely disposed band portion to the fabric with the unwoven transverse threads extending over and in spaced relation with the edge of the fabric.

4. A foldable edge binding comprising an elongated strip having woven band portions at each side to be applied on opposite sides of the portion being bound and having an intermediate middle fold portion of unwoven transverse flexible strands.

5. A foldable edge binding comprising an elongated strip of material having side securing band portions of woven warp and weft strands to be applied on opposite sides of the portion being bound, and an intermediate longitudinally extending middle fold portion through which the weft strands are exposed as unwoven transverse flexible strands foldable over the edge of the portion being bound and individually yieldable in use.

MARY BURNLEY GWATHMEY.
